UNITED STATES PATENT OFFICE.

PATRICK P. LA MONTAGNE, OF BOURBONNAIS, ILLINOIS, ASSIGNOR, BY MESNE ASSIGNMENTS, TO POPE MACHINE COMPANY, OF KANKAKEE, ILLINOIS, A CORPORATION OF ILLINOIS.

KNITTING MACHINE.

Application filed November 22, 1918, Serial No. 263,727. Renewed June 23, 1922. Serial No. 570,381.

To all whom it may concern:

Be it known that I, PATRICK P. LA MONTAGNE, a citizen of the United States, residing at Bourbonnais, county of Kankakee, State of Illinois, have invented an Improvement in Knitting Machines, of which the following description, in connection with the accompanying drawing, is a specification, like characters on the drawing representing like parts.

This invention relates to any type of knitting machine wherein it is necessary to throw some of the needles out of action during the knitting operation, and more particularly to the circular type of knitting machine wherein during predetermined periods reciprocating knitting is performed as, for instance, in the knitting of the heel and toe during the knitting of stockings.

20 The invention in some respects involves the type of mechanism made the subject of my application Serial No. 205,979, filed December 7, 1917.

The invention has for its object to provide a knitting machine in which each needle is provided with a separate jack mounted in the same groove with the needle and inwardly from the needle, each needle and jack being provided with co-operating shoulders.

The invention has for its further object the provision of means such as a second or additional projecting cam whereby the jacks are restored to the same position at the end 35 of the projecting movement of the needle notwithstanding any adjustment which may be made to provide for varying the movement of the needle as in lengthening and shortening the stitch.

40 While the invention is of value in connection with machines utilizing varying types of needles it is particularly valuable in the case of, and the invention particularly relates to those types of, knitting machines 45 wherein the so-called separate latch needles are employed, that is, needles in which the hook member and the co-operating latch member are physically separate and independent parts.

50 The invention has for its further object the provision of a needle projecting cam acting directly upon the needle and mounted

upon the cylinder in such a manner as to move vertically with the cylinder and rotarily with respect to the cylinder. 55

These and other objects of the invention will appear more fully from the accompanying description and drawings and will be particularly pointed out in the claims.

In the drawings which show a well known 60 and ordinary type of circular knitting machine with a preferred embodiment of the present invention,

Figure 1 is a view chiefly in central vertical cross-section of a portion of the knitting machine; 65

Fig. 2 is a detail in transverse cross-section showing the connection between the needle projecting cam ring and the needle retracting cam ring; 70

Fig. 3 is a top plan view partially in horizontal section and partially broken away and eliminating features unnecessary to a disclosure of the invention of the construction shown in Fig. 1; 75

Fig. 4 is a side elevation of the jack;

Fig. 5 is an end elevation of the jack;

Fig. 6 is a transverse cross-section enlarged of the jack taken on the line 6—6 of Fig. 5; 80

Fig. 7 is a detail chiefly in vertical cross-section taken on the line 7—7 of Fig. 3 of a portion of the cylinder of the machine and adjacent parts showing one of the picking instrumentalities for elevating the separate jack to throw the needles out of action; 85

Fig. 8 is a diagrammatic view showing the general relation of the needle, separate jack, picker, and cams when the jack is raised into position to throw the needle out 90 of action;

Fig. 9 is a view similar to Fig. 8 showing the needle, separate jack, dropper, and cams when the jack is depressed to bring the parts into knitting position. 95

In view of the nature of the invention it will be unnecessary either to illustrate or describe in detail the general features and construction of a knitting machine or of the knitting machine of the particular type herein illustrated further than those particularly concerned with the operation of the needle. 100

For convenience in disclosing the inven-

tion the movement of the needle to yarn receiving position will be referred to as the "projecting movement" or movement to "projected position"; movement of the 5 needle in the opposite direction will be referred to as the "retracting movement" or the movement to "retracted position"; direction toward the needle bed will be referred to as "inner" and direction away from the 10 needle bed as "outer"; direction toward the hook end of the hook member or the point of the latch member as "forward" and the opposite direction as "rearward"; direction lengthwise of the hook and latch members 15 will be referred to as "longitudinal", direction through the members from face to face as "lateral" and direction in or parallel with the general plane of the members as "transverse"; but it will be understood that these 20 and similar terms are relative only and are not to be taken as otherwise limiting the invention.

In the particular form of knitting machine herein illustrated for the purpose of disclosing 25 the invention the machine embodies a suitable circular bed plate 10 on which is centrally mounted a cylinder carrier 11 supported by a rod 12. On the cylinder carrier 11 is mounted the usual needle cylinder 13. 30 Surrounding the needle cylinder and concentric therewith and supported by the bed plate is the usual skeleton cylinder 14 the spaces between the bars 15 of which radially align with the needle grooves 16 in the exterior wall of the cylinder.

The knitting machine needles illustrated are of the type disclosed in my applications Serial No. 251,806, filed August 28, 1918 and Serial No. 362,878 filed March 2, 1920. This 40 type of needle comprises the two separate and independent members, the hook member 17 and the latch member 18. In this general type of needle one of the members is actuated from the other which in turn is 45 actuated by the cams of the knitting machine, and, in the form shown, the latch member receives its actuation from the hook member. The hook member in the form illustrated is provided with a shoulder or 50 butt 19 to co-operate with the needle projecting cam of the machine while the shank 20 of the hook member is provided with a shoulder 21 which in this case co-operates with a separate jack 22 which in turn is actuated by the needle retracting cam of the 55 machine.

The hook member of the needle forward of the shank or at the forward end of the shank is enlarged transversely to form a 60 body portion provided with an opening 23 extending laterally therethrough. The end walls 24 and 25 constitute shoulders which contacting with the latch member insure the proper relative movement of the needle 65 members. The hook member 17 is slotted

longitudinally and transversely at its forward end to receive and guide the forward end of the latch member.

The latch member 18 is made of thin sheet metal and of such thickness that it may readily move in the slot in the forward end of the hook member to bring its point 26 into and out of co-operative relation with the hook 70 27 on the hook member. The rearward end of the shank of the latch member has a portion 28 extending transversely from the main body of the shank. This portion or butt section 28 of the latch is located within the opening 23 of the hook member and is formed frictionally to engage the side walls 75 80 of the needle slot and effect the required retarding action with respect to the movement of the hook member and also presents at its rearward and forward ends suitable shoulders co-operating respectively with the 85 shoulders 24 and 25 of the hook member.

The needle movements are secured by the aid of a separate jack and on the broad principles of operation made the subject of my application Serial No. 205,979, filed December 7, 1917. In this invention, however, the separate jack embodies novel features of construction and position and the movements of the needle and jack are secured in a novel manner.

The use of the separate jack enables the needle to be thrown out of action and returned to knitting position when required with the minimum amount of movement, with the minimum amount of friction, without danger of binding or breakage, and without rendering it necessary to project the needle beyond its normal yarn receiving position. The separate jack is arranged to operate in the needle slot and inward of the 100 105 needle.

The separate jack itself in the preferred form illustrated and as shown more in detail in Figs. 4, 5 and 6 is preferably formed, as are the parts of the needle itself, out of sheet 110 metal by a stamping or cutting operation so as to form and space the shoulders thereof with extreme accuracy. This jack 22 comprises a shank having at its forward end an outward projection 29 presenting a shoulder 115 30 to co-operate with the shoulder 21 of the hook member of the needle. Near its rear end the jack is provided with the outwardly projecting butt 31 which passes between the bars 15 of the skeleton cylinder, when used, 120 and which is acted upon by the cams. In the rear of the butt 31 the separate jack may be provided with divergently bent fingers 32 and 33 to pass behind adjacent bars of the skeleton cylinder and thus prevent any 125 danger of the jack coming out from the needle slot. In addition the shank of the jack is bent slightly as shown in Fig. 5 so that it will have friction with the side walls of the needle slot.

The yarn 34 may be fed to the needles in any suitable manner as through a guide eye 35 which extends beneath the hook of the hook member and is supported from a suitable revolving carrier 36.

The needles draw the yarn down over a suitable work engaging portion of the cylinder which is herein shown as the upper surface of the sinkers 37. These sinkers are of a familiar type and are mounted to slide radially in grooves in an annular sinker cylinder 38 and an annular sinker guide 39 both rigidly secured to the upper end of the cylinder 13 in the usual manner.

15 The usual retracting cam 40 is carried by the cam ring 41 mounted in the bed plate 10 to rotate concentrically with the cylinder in the usual manner and is driven by the gear ring 42 from the gear 43 in the usual manner.

20 This retracting cam 40 acts upon the jack butts 31 and has associated with it a jack projecting cam 44 formed in the cam ring 41 and also acting upon the jack butts 31.

The projecting movement of the needle is given by a separate projecting cam 45 formed in a projecting cam ring 46 rotarily supported in the sinker guide 39. This cam ring 46 is flanged at 47 and held in place by a flange ring 48 screwed to the bottom surface of the sinker guide 39.

Rotation of the projecting cam ring 46 is secured by connecting it to the usual cam ring 41. This connection may be made by a post 49 secured at 50 to the cam ring 41 and projecting upwardly therefrom into an opening 51 formed in a lug 52 projecting laterally from the projecting cam ring 46. Set screws 53 in the lug 52 contact with the post 49 and enable an accurate relative adjustment to be made between the two cam rings.

This projecting cam 45 acts upon the shoulder or butt 19 formed upon the hook member of the needle and is the cam which gives the projecting movement to the needle.

45 The retracting movement of the needle is given through the agency of the separate jack and is effected by the retracting cam 40 acting upon the jack butt 31. The jack projecting cam 44 is for the purpose of insuring the jack butts being left in proper position to co-operate with the mechanism for throwing the needles out of and into action such as the usual cam and picker mechanism.

This jack projecting cam for this purpose is especially desirable when, as in the machine illustrated, the stitch is lengthened and shortened by raising and lowering the cylinder and needle projecting cam with respect to the needle retracting cam. The jack projecting cam being formed in the vertically stationary cam ring does not partake of the vertical movement of the needle projecting cam and consequently, no matter what may be the position of the needle projecting cam, the jack butts when they ride over the por-

tion 54 of the jack projecting cam are left in proper position to co-operate with the cam and picker mechanism. This jack projecting cam 44 is relieved or cut back throughout its periphery between the portions 54 so that when the cylinder is raised or lowered to lengthen or shorten the stitch only the few jacks over the portions 54 are moved in their slots, thus reducing the force required to raise and lower the cylinder.

The normal knitting operation of the machine will be readily apparent. The needles are given their projecting movements to carry them to yarn receiving position by the action of the projecting cam 45 on the shoulder 19 of each needle and the retracting movements of the needles are effected by the retracting cam 40 acting upon the upper surface of the butts 31 of the jacks. Each needle and its jack thus moves together except for such slight relative movement as may be due to the separation at the shoulder 21 when the needle is in projected position with the cylinder adjusted below its highest position.

When the machine changes from circular work to reciprocating work and back again it is necessary to employ a mechanism for throwing certain of the needles out of action and then restoring them into action. Any suitable or well known type of mechanism may be employed in connection with the separate jack needle herein disclosed making only such slight changes of adjustment and position as may be necessary to adapt it. For this purpose a well known type of mechanism, familiar to those skilled in the art and in its main features already illustrated in my aforesaid application Serial No. 205,979, filed December 7, 1917, is herein illustrated and it will therefore be unnecessary to describe the details of the construction and operation of such a mechanism.

When reciprocating knitting begins it is common to throw a portion or an entire set of the needles out of action. These needles are usually selected by being provided with butts of greater radial length than the butts of those needles that are to continue in action and the same principle is here employed in that the butts of the jacks for these needles are made respectively of greater length than the other needles. This set of needles may be thrown out of action by a suitable wedge-shaped cam 55 mounted upon a shaft 56 rotatably and longitudinally movable in a bearing 57 radially supported from the gear ring 42. This cam 55 during the ordinary circular knitting operation stands in elevated position and travels in a path above the jack butts 31 and thus clears all the butts. When one set of needles is to be thrown out of action the shaft 56 is rotated and at the same time moved longitudinally.

4

dinally outwardly to bring the point of the cam 55 into its depressed position below the path of the butts of the separate jacks of these needles which butts are longer than 5 those of the other jacks. This movement of the cam 55 may be effected manually or automatically; in the latter case by some means such as the automatic positioning of the cam 58 in the path of the crank arm 59 extending from the shaft 56. When the gear ring is rotated with the cam 55 thus depressed the upper surface of the cam rides beneath the longer butts of the jacks and projects these jacks to a position where the 15 butts are caught by and ride along over the surface 60 of the cam section forming the retracting cam 40 and the needles corresponding to these jacks are thus projected no further than they are in the normal knitting operation and as their jacks are out of reach of the retracting cam 40 these jacks and consequently these needles remain out of action.

When this section of the needles is to be 25 restored into knitting position the cam 55 is swung upwardly and moved inwardly to bring its lower surface above the butts of all the jacks so that as the gear ring is rotated all the jacks are retracted or restored 30 to a position where their butts are within the path of the retracting cam 40. This operation may be performed either manually or by the usual type of automatic mechanism.

35 In the formation of reciprocating work such as the knitting of the heel and toe sections of a stocking after one section of needles has been thrown out of action it is necessary gradually to reduce the number of needles remaining in action and then 40 gradually to restore those needles to knitting action. In this invention a usual type of picker and dropper mechanism is illustrated for this purpose which instead of acting upon the butts of the needles is so adjusted and arranged as to act upon the butts of the separate jack members and respectively picks and depresses the jack butts out of and into the path of the retracting cam 50 40.

In the construction illustrated the picker and the dropper mechanism are shown as 55 separate instrumentalities. When the reciprocating knitting is taking place the gear ring 42 is given an oscillating or reciprocating motion. Upon this gear ring at one side are mounted the pickers 61 and at an opposite point the dropper 62 and all are constructed and operated in a manner well 60 known to those skilled in the art except that the effective ends of the picker and dropper are adjusted to co-operate with the butt of the jack and act to shift the jack butt.

The pickers 61 act in a familiar manner 65 pivoting vertically in the horizontally piv-

oted posts 63 on the gear ring 42 and having their shanks guided in cam slots of the guide plate 64. They remain idle during circular knitting but at each change of direction of movement these pickers alternately pass beneath the butts of one or more of the jacks of the needles remaining in action thus throwing these needles out of action. Thus the knitting is gradually narrowed.

The widening operation takes place in a 70 similarly familiar manner through the action of the dropper 62 which is shown as a symmetrically shaped device horizontally and vertically pivoted in a bearing 65 on the gear ring 42. It is preferably called into 80 operation by automatic mechanism such as the sliding cam plate 66 automatically actuated by the crank arm 67 in the mechanism of the machine. At the required time this dropper is guided to a position in line 85 with the butts of successively elevated or projected jacks so that at the end of each reciprocation the jack butts at the end of the row of needles thrown out of action are caught by the dropper and retracted. In 90 the widening operation the dropper is generally arranged to depress a greater number of jacks than the pickers elevate allowing the pickers to remain in operation, each elevating say one jack at the end of each 95 reciprocation and the hopper depressing two jacks at each end of each reciprocation so that as a net result one jack is brought back into operative position at each end of each reciprocation. But the particular construction and operation of the picker mechanism and the dropper mechanism is not involved in this invention and this general explanation will be sufficient to those skilled in the art.

100 It is important that the hook member and the latch member shall always retain when in yarn-receiving position a fixed relation to the work engaging portion or top of the cylinder, in the form shown, the 110 top of the sinkers. This requirement is particularly true of the separate latch needle and of the latch member thereof. It is frequently desirable to vary the length 115 of the loop by varying the extent to which the needle is retracted, the yarn being drawn out by the cylinder needle over the dial needles when the dial is employed or over the top of the cylinder when the dial is not employed. The lengthening of the 120 stitch is accomplished by changing the relative position of the cylinder and the retracting cam 40 to increase the distance therebetween. In order that the latch member may occupy when in yarn-receiving 125 position always the same relation to the top of the cylinder the projection cam must float or move with the cylinder as in my before-mentioned application Serial No. 205,979, filed December 7, 1917. The pro- 130

jecting cam in the present construction is the cam 45 which acts upon the shoulder or butt 19 of the hook member of the needle and the movement of this cam with the cylinder is secured by the construction already described in which this cam is rotarily mounted upon the annular sinker guide which in turn is mounted upon the cylinder, the alinement of the retracting and projecting cams being secured by the post construction already described.

While but one set of operating cams 45, 40 and 44 have been illustrated and described it will of course be understood that 15 as many such operating cams shall be employed as there are yarn feeds.

Having fully described my invention, what I claim as new and desire to secure by Letters Patent is:

- 20 1. A knitting machine comprising a needle bed, a needle longitudinally reciprocable in the needle bed, a jack reciprocable with and with respect to said needle, a retracting cam acting upon the jack to retract the jack and therethrough the needle, a projecting cam acting directly on the needle, means for longitudinally adjusting the needle bed and projecting cam with respect to the retracting cam to vary the length of stitch, and 30 means for projecting the jack independently of the needle.
- 25 2. A knitting machine comprising a needle bed, a needle longitudinally reciprocable in the needle bed, a jack reciprocable with and with respect to said needle, a retracting cam acting upon the jack to retract the jack and therethrough the needle, a projecting cam acting directly on the needle, means for longitudinally adjusting 35 the needle bed and projecting cam with respect to the retracting cam to vary the length of stitch, and a jack projecting cam for projecting the jack independently of the needle.
- 30 45 3. A knitting machine comprising the construction defined in claim 1 in which the jack is mounted rearwardly of the needle and in which oppositely disposed shoulders on the needle and jack effect the movement 50 of the needle and the jack one from the other.
- 45 4. A knitting machine comprising the construction defined in claim 1 in which the jack is located in the rear of the needle, in which the needle is formed at its rearward end 55 with a shoulder and the jack at its forward end with a shoulder, the said shoulders cooperating to effect conjoint movement of the needle and jack.
- 50 5. A circular knitting machine comprising 60 a bed plate, a needle cylinder vertically adjustable therein, a needle longitudinally reciprocable in said cylinder, a jack longitudinally reciprocable with and with respect to said needle, a projecting cam acting directly on the needle and vertically adjustable 65
- 55 70 75 80 85 90 95 100 105 110 115 120 125 130 with the cylinder, a retracting cam held against vertical movement in the bed plate and acting upon the jack to retract the jack and therethrough the needle, and a jack projecting cam held against vertical movement in the bed plate and acting to project the jack independently of the needle.
6. A circular knitting machine comprising a bed plate, a needle cylinder vertically adjustable therein, a needle longitudinally reciprocable in said cylinder, a jack longitudinally reciprocable with and with respect to said needle, a projecting cam acting directly on the needle and vertically adjustable with the cylinder, a retracting cam held against vertical movement in the bed plate and acting upon the jack to retract the jack and therethrough the needle, a jack projecting cam held against vertical movement in the bed plate and acting to project the jack independently of the needle, and means for coupling the said cams together to maintain their horizontal position and permit change in their relative vertical position.
7. A circular knitting machine comprising a bed plate, a needle cylinder vertically adjustable therein, a needle longitudinally reciprocable in said cylinder, a jack longitudinally reciprocable with and with respect to said needle, a projecting cam acting directly on the needle and vertically adjustable with the cylinder, a retracting cam held against vertical movement in the bed plate and acting upon the jack to retract the jack and therethrough the needle, a jack projecting cam held against vertical movement in the bed plate and acting to project the jack independently of the needle, and means for coupling the said projecting cams together to maintain their horizontal position and permit change in their relative vertical position.
8. A knitting machine comprising a needle cylinder, an annular sinker guide secured to the top of the cylinder exteriorly thereof and an annular needle operating cam ring rotarily mounted in said sinker guide exteriorly of said cylinder whereby vertical movement of the cam ring with respect to said cylinder is prevented and rotary movement with respect to said cylinder permitted.
9. A knitting machine comprising a bed plate, a needle cylinder vertically adjustable in the bed plate, a cam ring rotarily mounted in the bed plate exteriorly of the cylinder and provided with a retracting cam, a projecting cam ring provided with a projecting cam mounted exteriorly of said cylinder above said retracting cam, and means for preventing vertical movement and permitting rotary movement of said projecting cam ring with respect to said cylinder.
10. A knitting machine comprising a bed plate, a needle cylinder vertically adjustable in the bed plate, a cam ring rotarily mounted

- ed in the bed plate exteriorly of the cylinder and provided with a retracting cam, a projecting cam mounted in said cam ring beneath the retracting cam, a projecting cam 5 ring provided with a second projecting cam mounted exteriorly of said cylinder above said retracting cam, and means for preventing vertical movement and permitting rotary movement of said projecting cam 10 ring with respect to said cylinder.
11. A knitting machine comprising the construction defined in claim 9 together with means for coupling the said cam rings together acting to permit a change in their 15 relative vertical positions while maintaining their horizontal relation.
12. A knitting machine comprising the construction defined in claim 10 together with means for coupling the said cam rings 20 together acting to permit a change in their relative vertical positions while maintaining their horizontal relation.
13. A knitting machine comprising the construction defined in claim 9 together 25 with a vertical post secured to one of said cam rings and passing through an aperture in the other of said cam rings whereby vertical relation of said cam rings may be changed without altering their horizontal 30 relation.
14. A knitting machine comprising a grooved needle bed, needles longitudinally slidable in said grooves and provided with transversely extending shoulders, a projecting cam 35 cooperating with said shoulders to give the required projecting movement to said needles, separate jacks mounted in said grooves rearwardly of said needles, said jacks engaging said needles to effect the re- 40 tracting movement of the needles, said jacks slidable in said grooves with and with respect to their respective needles and each presenting a shank and a transversely extending butt, and a retracting cam acting 45 upon said butt to give the required retracting movement to said jacks and therethrough to said needles.
15. A knitting machine comprising the elements defined in claim 14 together with 50 means acting selectively upon the jack butts to move the selected jack butts out of, and restore them into, the path of said retracting cam and thereby to throw the selected needles out of, and into, action.
16. A knitting machine comprising the elements defined in claim 15 together with a second projecting cam acting upon the jack butts simultaneously with the action of the first projecting cam upon the needle shoulders 60 whereby the jack butts when in action are always brought to the same position at the end of the projecting movement of the needles.
17. A knitting machine comprising a 65 needle bed, a separate latch needle com-
- prising relatively bodily movable latch and hook members longitudinally reciprocable in the needle bed, a jack mounted in the needle bed inwardly of and coacting with one of the members to effect its retracting 70 movement, and means acting upon the needle and jack to effect the knitting function.
18. A knitting machine comprising the construction defined in claim 17 in which the coacting jack and needle members are 75 mounted and move in the same slot in the needle bed.
19. A knitting machine comprising a needle bed, a separate latch needle comprising relatively bodily movable latch and hook members, a jack mounted inwardly of and in the same slot with the needle and coacting with one of the needle members to effect only rearward movement thereof, a projecting cam acting upon the said needle 80 members, a retracting cam located rearwardly of the projecting cam and acting upon the jack.
20. A knitting machine comprising a separate latch needle comprising a hook member and a latch member slidable on the hook member for movement independently thereof, a needle positioning device actuatable with and also with respect to the needle, means 85 acting upon the needle positioning device to actuate it and, therethrough, the needle, means acting directly on the needle to actuate the same in one direction, means for longitudinally adjusting the second mentioned means with respect to the first mentioned means to vary the length of stitch, and means for positioning the needle 90 positioning device independently of the needle.
21. A knitting machine comprising a needle bed, a needle longitudinally reciprocable therein comprising a hook member and a latch member slidable on the hook member for independent movement and also movable therewith, a needle positioning device reciprocable with and with respect to the needle; a retracting cam acting upon the needle positioning device to retract it and, therethrough, the needle, a projecting cam 105 acting directly on the needle to actuate it, means for longitudinally adjusting the needle bed and projecting cam with respect to the retracting cam to vary the length of stitch, and a projecting cam for projecting the needle positioning device independently of the needle.
22. A knitting machine comprising the construction defined in claim 20 in which the needle positioning device is disposed horizontally of the needle and in which oppositely disposed shoulders on the needle 110 and the said device effect movement of the needle and the said device one from the other.
23. A circular knitting machine comprising a support, a needle-cylinder vertically 115

adjustable therein, a needle longitudinally reciprocable in the cylinder comprising a hook member and a latch member slidable thereon for independent movement and also 5 movable therewith, a needle positioning device longitudinally reciprocable with and with respect to the needle, means acting directly on the needle and vertically adjustable with the cylinder, means held against

vertical movement in the support and acting upon the device to retract it and, there-through, the needle, and means held against vertical movement in the support and acting to project the device independently of the needle. 10 15

In testimony whereof, I have signed my name to this specification.

PATRICK P. LA MONTAGNE.
